CLAIM

The ornamental design for a golf club grip with surface ornamentation, as shown and described.

DESCRIPTION

FIG. 1 is a perspective view of a right-handed embodiment of a golf club grip with surface ornamentation, showing my new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof, the bottom plan view is an identical view thereof;

FIG. 7 is a perspective view thereof, shown in a first used condition;

FIG. 8 is a perspective view of a left-handed embodiment of the golf club grip with surface ornamentation;

FIG. 9 is a front elevation view thereof;

FIG. 10 is a rear elevation view thereof;

FIG. 11 is a left-side elevation view thereof;

FIG. 12 is a right-side elevation view thereof;

FIG. 13 is a top plan view thereof, the bottom plan view is an identical view thereof; and,

FIG. 14 is a perspective view thereof, shown in a second used condition.

The dot-dash broken lines shown in the drawings depict the bounds of the golf club grip with surface ornamentation and form no part of the claimed design.

The dash-dash broken lines depicting the hands of a user in FIGS. 7 and 14 depict environmental subject matter that forms not part of the claimed design, while the remaining dash-dash broken lines shown in the drawings depict portions of the golf club grip with surface ornamentation that form no part of the claimed design.

The use of stippling indicates a contrasting appearance with the adjacent line-shaded portion of the golf club grip with surface ornamentation.
